UNITED STATES PATENT OFFICE.

JAMES P. SEXTON, OF LOS ANGELES, CALIFORNIA.

WATERPROOF PLASTER-BOARD AND METHOD OF MAKING SAME.

1,325,883.

Specification of Letters Patent. Patented Dec. 23, 1919.

Application filed December 19, 1917. Serial No. 207,856.

To all whom it may concern:

Be it known that I, JAMES P. SEXTON, a citizen of the United States, residing at Los Angeles, in the county of Los Angeles, State 5 of California, have invented new and useful Improvements in Waterproof Plaster-Board and Methods of Making Same, of which the following is a specification.

This invention relates to plaster board, 10 plaster lath, and like articles, which comprise a body of plaster or other plastic or cementitious substance and one or more facing sheets of paper or the like; and the invention further particularly relates to such 15 an article in which the paper facing sheets are waterproofed.

According to my invention the paper facing sheets may be waterproofed in any desired manner; in a typical case, as herein- 20 after described, they may previously be waterproofed with a bituminous substance, such as tar. In typical instances I use what is commercially known as tarred paper or tarred felt; being preferably a soft finished, 25 tarred paper, in which the paper is thoroughly impregnated with the waterproofing substance.

In the use of such waterproofed papers, it has been impracticable or impossible to 30 join the plastic substances with the waterproofed paper. The very fact that the paper is waterproofed makes it very difficult to form a bond between the moist plastic substance and the paper. This is particularly 35 true where the plaster is not bonded to the paper by a mechanical bond of some sort. Where the paper and plaster are mechanically bonded, a waterproofed paper can, and has been, and is now, used by me in such 40 construction as is shown by my Patent No. 1,115,593, November 3, 1914, and reissued June 5, 1916, No. 14,148, and shown also in the following named patents: plaster lath, No. 1,205,399, Nov. 21, 1916; plaster lath, 45 No. 1,205,360, November 21, 1916; and applications as follows: method of making plaster lath, S. N. 129,650, Nov. 6, 1916; plaster lath, S. N. 187,331, Aug. 21, 1917.

In such forms as herein referred to, one 50 or both of the face sheets may be mechanically bonded. And my present invention may be applied to such mechanically bonded structure as well as to a plain plaster board or the like.

For the purpose of fully explaining my 55 present invention I illustrate herewith, in

the accompanying drawings, a plain plaster board and a plaster lath which is known commercially as "buttonlath"; Figure 1 being a section showing the structure of a 60 plain plaster board; and Fig. 2 being a similar structure showing the structure of such a plaster lath.

Such plaster boards and plaster laths are commonly made by interposing a body 10 65 of plastic substance between two sheets of paper or other fibrous substance, shown at 11 and 12. In the case of the plain plasterboard, both these sheets 11 and 12 are plain papers; while in the case of the plaster lath 70 both facing sheets may be in the form shown at 12 in Fig. 2, with apertures at 12^a, allowing protuberances or buttons 10^a to be formed of the plaster body 10; or one of the sheets may be in this apertured form and 75 the other, as shown at 11, may be in plain form. Regardless of any peculiar shaping of the facing sheets, and whether or not there is a mechanical bond between the plaster and the sheet, my method of bonding the waterproofed sheet to the plastic body may be used.

It is now the common practice to manufacture such plaster boards and the plaster laths by continuously laying a layer of 85 moist or unstable plastic or similar substance upon a continuous length of paper and then laying another continuous length of paper over the plastic layer; suitable pressure being applied to press the plastic layer 90 out into a uniform thickness. The papers used may be waterproofed in any manner, preferably waterproofed with a substance which melts or becomes soft at a fairly low temperature. Also, although this is not 95 necessary, for the purpose of my invention the paper is preferably a relatively soft rough-surfaced paper, and is waterproofed with a bituminous substance. Now, as hereinbefore stated, under ordinary circumstances the moist or unstable plastic substance which is laid between the sheets of such paper will not incorporate with the paper owing to the waterproof quality of the same. But I cause such incorporation to 100 be made by suitably heating the plasterboard or plasterlath, either at the time of formation or at some time subsequent. Although I may cause the heating to take place during setting, I prefer to heat after 105 partial or complete setting or during the latter stages of setting. I heat the plaster

board or plasterlath to a temperature which is sufficient to cause the softening or melting of the bituminous waterproofing substance, but which is below the calcining temperature of the plaster; and this temperature is typically about 130° to 150° F. That is, this temperature is sufficient to cause the waterproofing substance to soften or melt, but it is not sufficient to deteriorate the plastic body. Heat of this degree of temperature need only be applied for a short interval; it does not need to be applied during the whole of the setting or drying operation of the plaster. By causing the waterproofing substance to soften or melt, the pores in the paper are opened up so that (where the heating is done before the plaster sets) the moist or unstable plastic substance may permeate the paper to a certain extent by entering such pores; and (whether the heating is done before or after setting of the plaster) the melted or soft waterproofing substance also penetrates the plastic substance to a certain extent. The substances are then allowed to cool, or cool and set, in their inter-permeated state. And by this means a bond is formed between the plastic body and the waterproofed paper facing, which bond extends over the whole of the surfaces of the body and paper, and causes the body and paper to be most thoroughly incorporated and bonded together. When the body and paper sheets are once bonded in this manner, the bond is as strong as or stronger than the plastic body or the paper sheet itself. In fact, it is almost impossible to tear the paper sheet from the body without breaking or tearing one or both.

40 The foregoing description applies more particularly to the use of paper which has been previously waterproofed with a suitable substance. But it is not necessary that the paper be waterproofed before the application of the plastic or cementitious substance thereto, as such waterproofing can be made to take place during the process of formation of the plaster board or the like. For instance, I have found it possible to provide a plastic substance which, while it forms the body of the plaster board, contains in it a waterproofing substance, such as certain kinds of glue, or bituminous substance or the like, which melt or soften upon heating and which will permeate the outer paper sheets. For instance, a greasy waterproofing substance may be used, in this instance, or in the instance heretofore explained in this specification, said substance softening or liquefying upon being heated and permeating the paper; and then, when solidifying, forming the same kind of bond between the paper and the plastic body as is hereinbefore explained.

65 It will be seen that my invention is pri-

marily a method of bonding which may be applied to any form of plaster board or plasterlath, etc., whether composed of one or more plastic bodies or sheets, and regardless of the shape, etc., of those sheets. Applied to a plain plaster board it causes a thorough bond to be made where heretofore it has been impossible or highly difficult to make such a bond; applied to a plaster lath in which there is a mechanical bond, it adds its effectiveness by providing a bond which is co-extensive with the paper and plaster.

I do not limit my invention to the particular details herein described except as is indicated by the following claims which are intended to cover the invention in its broad as well as its specific aspects.

Having described a preferred form of my invention, I claim:

1. The herein described method of making a waterproof plaster board or the like, which comprises the placement of an unstable plastic substance in contact with a porous sheet waterproofed with a material which is softened by heat and to which the cementitious substance is permeable and heating them to a temperature sufficient to soften the waterproofing of the sheet, to allow the waterproofing and the plastic substance to inter-permeate, and then allowing them to cool and set.

2. The herein described method of making a waterproof plaster board or the like, which comprises the placement of an unstable plastic substance in contact with a porous sheet waterproofed with a material which is softened by heat and to which the cementitious substance is permeable and heating them to a temperature sufficient to soften the waterproofing of the sheet but insufficient to deteriorate the plastic substance to allow the waterproofing and the plastic substance to inter-permeate, and then allowing them to cool and set.

3. The herein described method of making a waterproof plaster board or the like, which comprises the placement of a moist plaster in contact with a sheet impregnated with a bituminous substance, and heating them to a temperature sufficient to soften said bituminous substance and insufficient to calcine the plaster to allow the softened substance and the moist plaster to inter-permeate, and then allowing them to cool and set.

4. The herein described method of bonding a cementitious substance and a sheet waterproofed with a substance softened or melted by heat and to which the cementitious substance is permeable, which comprises placing the substance and sheet in contact, heating them to soften the waterproofing substance to allow it to permeate the cementitious substance, and then allowing them to cool.

5. The herein described method of bonding a plaster and a paper impregnated with bituminous substance, which comprises placing the plaster in contact with the 5 paper, and heating them to a temperature sufficient to soften the bituminous substance but insufficient to calcine the plaster.
6. The herein described method of making a waterproof plaster board or the like, 10 which comprises the placement of a waterproofing capable of being softened by heat and an unstable plastic material which is permeable to the softened waterproofing material in contact with a sheet permeable 15 to the softened waterproofing material, and heating them to a temperature sufficient to

soften the waterproofing, to allow the waterproofing to permeate the plastic material and the sheet, and then allowing them to cool and set.

7. A waterproof plaster board, comprising a body of plaster and a facing sheet impregnated with a bituminous substance, the plaster and the bituminous substance being incorporated by interpenetration with 25 each other over their face of contact.

In witness that I claim the foregoing I have hereunto subscribed my name this 4th day of December, 1917.

JAMES P. SEXTON.

Witness:

V. BERINGER.
